UNITED STATES PATENT OFFICE

2,001,472

LAMP

Henry J. Sauer, Fairfield, Conn., assignor to The Kilborn-Sauer Company, Fairfield, Conn., a corporation of Connecticut.

Application January 9, 1935, Serial No. 1,008

12 Claims. (Cl. 240—83)

The present invention relates to an improvement in lamps, particularly for automobile use, and has for an object to provide a lamp in which the usual detachable rim is dispensed with, to the end that a lamp is produced which is more attractive in appearance, and in which the usual shoulder or seam of the rim is eliminated, so that the structure more readily lends itself to stream-line design, a stronger construction is provided, and a lamp is produced of greatly simplified manufacture and assembly. A further object is to provide a glass cup-shaped insert member for the lamp which in cooperation with the casing constitutes means for retaining the lens in place, and which has the further functions of providing a complete circumferential reinforcement to the lamp casing, a reflector, and an interior surface which may be readily cleaned without danger of destroying the reflector surface. Another object is to provide a tail light lamp in which the lens for illuminating the license plate is an integral part of the cup-shaped insert member. A still further object is to provide a lamp structure in which the manufacture and assembly of the parts is greatly simplified.

With the above and other objects in view embodiments of my invention are shown in the accompanying drawing, and these embodiments will be hereinafter more fully described, with reference thereto, and the invention will be finally pointed out in the claims.

In the drawing:

Fig. 1 is a side elevation of a tail-light lamp, according to one exemplary embodiment of my invention.

Fig. 2 is a vertical sectional view, with the lamp turned in opposed relation to the lamp as shown in elevation of Fig. 1.

Fig. 3 is a front elevation of the lamp casing before insertion of the lens, and showing the position of the forward rim portion preparatory to insertion of the lens.

Fig. 4 is a front elevation of the lamp with the lens in place.

Fig. 5 is a side elevation of a head-light lamp, according to my invention.

Fig. 6 is a vertical sectional view thereof.

Similar reference characters indicate corresponding parts throughout the several figures of the drawing.

Referring to the drawing, and particularly to Figs. 1 to 4 thereof, the tail-light lamp according to the illustrated exemplary embodiment of the invention shown therein, comprises a cup-shaped lamp casing 10 formed of suitable metal and pref-

erably spun to shape, the circumferential wall of the casing slightly converging inwardly from front to rear and provided at the forward open end with an inwardly bent flange 11, preferably having a curvature to conform to the front curved surface of the inserted lens, as will hereinafter more fully appear. Within a flanged central opening 12 in the rear wall of the casing there is secured the usual lamp socket member 13 and to the outer surface of the rear wall there is secured a suitable bracket 14 for attachment of the lamp to the automobile structure.

In the lower portion of the casing there is formed a rectangular opening 15 for the purpose of illuminating the license plate, this opening adapted, as will presently more fully appear, to receive the lens portion of the glass insert member. The provision of the opening 15 produces a relatively narrow rim portion 16 at the forward end of the casing extending slightly less than half of the diameter of the casing. At one end this portion 16 is separated from the casing by a seam or cut 17 preferably in line with one end of the opening 15, this cut preferably being produced after the forming of the casing and the cutting out of the opening 15. As shown in Fig. 3 this rim portion 16 is intended to be sprung outwardly to permit insertion of the glass cup member and the lens. A securing lip member 18 is secured to the end of the rim portion 16, as by spot-welding or other suitable means, and substantially corresponds in cross sectional shape to the cross sectional shape of the rim portion 16 and flange 11. This lip portion 18 overlaps the casing 10 and is secured thereto by means of a set-screw 19 engaged through the lip and screwed into a threaded hole 20 in the casing.

The glass cup member 21 is shaped to fit snugly within the casing 10 and is provided in its rear wall with a centrally disposed circular opening 22 surrounding the lamp socket member 13. The forward edge of the cup member is inwardly spaced from the flange 11 and constitutes a shoulder against which the inner surface of the circular front lens 23 engages. A rectangular section 24 of increased thickness is integrally formed with the cup member to engage in the rectangular opening 15 and constituting a lens for this opening. The engagement of the shoulder formed by the outer edges of this section with the walls of the opening 15 retains the cup member against circumferential displacement. In the forward edge of the cup member there is provided a notch or cut-out 25 at the point where

the inner end of the set-screw 19 projects through the hole 20.

The outer surfaces of the cup member, with the exception of the portion 24 may be silvered or otherwise coated with a substance to produce a mirror surface, as at 26.

In the operation of assembling the lamp the rim portion 16 is forced out as shown in Fig. 3 and the cup member inserted in the casing, the 10 flexibility of the casing in the non-secured relation of the rim portion 16 permitting this to be readily accomplished. The lens is then inserted with its edge engaged between the forward edge 15 of the cup member and the inwardly extending flange 11, whereupon the rim portion 16 is brought into its normal circumferential relation and is secured by the set screw 19. The curvature of the inwardly extending flange 11 which engages the convexly curved surface of the lens produces a wedging action as the rim portion 16 is drawn into its lens retaining position pressing the lens tightly against the forward edge of the cup member 21 and thereby snugly retaining the parts in assembled relation, without the use of 20 spring means such as are usually employed in lamp structures to prevent looseness and rattling of parts.

In Figs. 5 and 6 I have illustrated a modified form of the invention adapted to a head-light lamp. In this form the casing 27 is of bullet or other suitable shape and is provided at its forward edge with an inturned flange 28. A strut member 29 is inserted and secured within the casing and constitutes a support for the lamp socket member 30, as well as an abutment for the glass insert member 31 which is provided with a central opening 32 surrounding the socket member 30. The glass cup member in this case is of parabolic shape, except for the forward end portion which is shaped to conform to the inner slightly outwardly diverging surface of the casing. A cut-out 33 is provided in the forward edge of the cup member in which the end of the securing screw engages, as will presently more fully appear, and the outer surface of the cup member is silvered or otherwise provided with a mirror surface, as at 34.

The casing is provided with a seam or slit, as at 35, extending for a substantially distance rearwardly from the rim 11, so that the forward portion of the casing may be readily spread open to permit the insertion of the cup member and the glass lens 36, which lens, as in the form of the invention shown in Figs. 1 to 4, has its outer edge portion wedged between the forward edge of the cup member and the flange 28. A securing lip member 37 is attached to the casing at one side of the slit 35, as by spot-welding or other suitable means, and overlaps the casing at the other side of the slit, where it is provided with a set screw 38 which engages a threaded hole in the casing to thereby secure the parts in assembled relation.

I have illustrated and described preferred and satisfactory embodiments of the invention, but it will be obvious that changes may be made therein, within the spirit and scope thereof as defined in the appended claims.

Having thus described my invention what I claim and desire to secure by Letters Patent is:—

1. In a lamp, a cuplike casing having an inturned flange at its forward open end, said casing having a split opening extending from its forward edge rearwardly and whereby the forward open end may be opened beyond its normal

opening, means within said casing forming a shoulder inwardly spaced from said inturned flange, a lens having an outside diameter larger than the inside diameter of said inturned flange in its normal position and having its peripheral edge disposed and held between said shoulder and said flange, said lens being insertable in said casing by said opening of the forward end of said casing beyond its normal opening, and means securing said split open end to normally retain said 10 normal opening.

2. In a lamp, a cup-like casing having an in-turned flange at its forward open end, said casing having a split opening extending from its forward edge rearwardly and whereby the forward 15 open end may be opened beyond its normal opening, a cup-like insert member within said casing having a forward end forming a shoulder inwardly spaced from said inturned flange, a lens 20 having an outside diameter larger than the inside diameter of said inturned flange in its normal position, and having its peripheral edge disposed and held between said shoulder and said flange, said lens being insertable in said casing by said opening of the forward end of said casing 25 beyond its normal opening, and means securing said split open end to normally retain said normal opening.

3. In a lamp, a cup-like casing having an in-turned flange at its forward open end, said casing 30 having a split opening extending from its forward edge rearwardly and whereby the forward open end may be opened beyond its normal opening, a cup-like insert member of glass within said casing having a forward end forming a shoulder 35 inwardly spaced from said inturned flange, a lens having an outside diameter larger than the inside diameter of said inturned flange in its normal position and having its peripheral edge disposed and held between said shoulder and 40 said flange, said lens being insertable in said casing by said opening of the forward end of said casing beyond its normal opening, and means securing said split open end to normally retain said normal opening.

4. In a lamp, a cup-like casing having an in-turned flange at its forward open end, said casing having a split opening extending from its forward edge rearwardly and whereby the forward open end may be opened beyond its normal opening, a cup-like insert member of glass within said casing having a forward end forming a shoulder inwardly spaced from said inturned flange, a reflector coating upon the outer surface of said insert member, a lens having an outside diameter 55 larger than the inside diameter of said inturned flange in its normal position, and having its peripheral edge disposed and held between said shoulder and said flange, said lens being insertable in said casing by said opening of the forward 60 end of said casing beyond its normal opening, and means securing said split open end to normally retain said normal opening.

5. In a lamp, a cup-like casing having an in-turned flange at its forward open end, a lamp 65 socket supported in the rear wall of said casing, said casing having a split opening extending from its forward edge rearwardly and whereby the forward open end may be opened beyond its normal opening, a cup-like insert member of glass within 70 said casing having a forward end forming a shoulder inwardly spaced from said inturned flange, said member having an aperture in its rearward portion surrounding said socket, a lens having an outside diameter larger than the inside diameter 75

5 of said inturned flange in its normal position, and having its peripheral edge disposed and held between said shoulder and said flange, said lens being insertable in said casing by said opening of the forward end of said casing beyond its normal opening, and means securing said split open end to normally retain said normal opening.

6. In a lamp, a cup-like casing having an in-turned flange at its forward open end, said casing 10 having a split opening extending from its forward edge rearwardly and whereby the forward open end may be opened beyond its normal opening, means within said casing forming a shoulder inwardly spaced from said inturned flange, a lens 15 having an outside diameter larger than the inside diameter of said inturned flange in its normal position and having its peripheral edge disposed and held between said shoulder and said flange, said lens being insertable in said casing by said opening of the forward end of said casing beyond its normal opening, a lip secured to said casing at one side of said split and overlying said casing 20 at the other side of said split, and a set-screw securing said lip to said casing at said other side 25 of said split to normally retain said normal opening.

7. In a lamp, a cup-like casing having an in-turned flange at its forward open end, said casing 30 having a split opening extending from its forward edge rearwardly and whereby the forward open end may be opened beyond its normal opening, a cup-like insert member of glass within said casing having a forward end forming a shoulder inwardly spaced from said inturned flange, a lens 35 having an outside diameter larger than the inside diameter of said inturned flange in its normal position and having its peripheral edge disposed and held between said shoulder and said flange, said lens being insertable in said casing by said opening of the forward end of said casing beyond its normal opening, a lip secured to said casing at one side of said split and overlying said casing 40 the other side of said split, and a set-screw securing said lip to said casing at said other side of 45 said split to normally retain said normal opening, said insert member having a cut-out in register with said set-screw.

8. In a lamp, a cup-like casing having an in-turned flange at its forward open end, said casing 50 having a split opening extending from its forward edge rearwardly and whereby the forward open end may be opened beyond its normal opening, means within said casing forming a shoulder inwardly spaced from said inturned flange, a lens having an outside diameter larger 55 than the inside diameter of said inturned flange in its normal position, and having its peripheral edge disposed and held between said shoulder and said flange, said lens being insertable in said casing by said opening of the forward end of said casing beyond its normal opening, and means securing said split open end to normally 60 retain said normal opening, said flange and the outer margin of said lens engaged thereby being convexly curved whereby said margin is wedged between said flange and said shoulder.

9. In a lamp, a cup-like casing having an in-turned flange at its forward open end, and having 65 a license plate illuminating opening in its side wall, said casing having a split opening extending from its forward edge rearwardly to said license plate illuminating opening and whereby the forward open end may be opened beyond its normal openings, means within said casing

forming a shoulder inwardly spaced from said inturned flange, a lens having an outside diameter larger than the inside diameter of said inturned flange in its normal position and having its peripheral edge disposed and held between said shoulder and said flange, said lens being insertable in said casing by said opening of the forward end of said casing beyond its normal opening, and means securing said split open end to normally retain said normal opening. 10

10. In a lamp, a cup-like casing having an in-turned flange at its forward open end and having a license plate illuminating opening at its side wall, said casing having a split opening extending from its forward edge rearwardly to said license plate illuminating opening and whereby the forward open end may be opened beyond its normal opening, said split being contiguous to one end of said license plate illuminating opening, means within said casing forming a shoulder inwardly spaced from said inturned flange, a lens having an outside diameter larger than the inside diameter of said inturned flange in its normal position and having its peripheral edge 25 disposed and held between said shoulder and said flange, said lens being insertable in said casing by said opening of the forward end of said casing beyond its normal opening, and means securing said split open end to normally retain 30 said normal opening.

11. In a lamp, a cup-like casing having an in-turned flange at its forward open end and having a license plate illuminating opening in its side wall, said casing having a split opening extending from its forward edge rearwardly and whereby the forward open end may be opened beyond its normal opening, a cup-like insert member of glass within said casing having a forward end forming a shoulder inwardly spaced 35 from said inturned flange, and providing a lens for said license plate illuminating opening, a lens having an outside diameter larger than the inside diameter of said inturned flange in its normal position and having its peripheral edge 40 disposed and held between said shoulder and said flange, said last mentioned lens being insertable in said casing by said opening of the forward end of said casing beyond its normal opening, and means securing said split open end to normally 45 retain said normal opening.

12. In a lamp, a cup-like casing having an in-turned flange at its forward open end and having a license plate illuminating opening in its side wall, said casing having a split opening extending from its forward edge rearwardly and whereby the forward open end may be opened beyond its normal opening, a cup-like insert member of glass within said casing forming a shoulder inwardly spaced from said inturned 55 flange, said insert member having an outwardly thickened portion corresponding in shape to said license plate illuminating opening and engaged therein and forming a lens therefor, a lens having an outside diameter larger than the inside 60 diameter of said inturned flange in its normal position, having its peripheral edge disposed and held between said shoulder and said flange, said last mentioned lens being insertable in said casing by said opening of the forward end of said 65 casing beyond its normal opening, and means securing said split open end to normally retain said normal opening.
